TIME DELAY SWITCH

Carl H. Larson, Elkhart, Ind., assignor to The
Adlake Company, a corporation of Illinois

Application October 17, 1934, Serial No. 748,586

8 Claims. (Cl. 200—97)

This invention relates to switches that are operated to open or to close a circuit when something happens, or some condition arises that makes a change in a circuit desirable, but only 5 after a delay or time interval that is a matter of selection under the particular circumstance, and the principal object of the invention is to enable the switch maker to easily and cheaply insure that each switch will have the particular 10 delay selected for a good use.

This is achieved in magnetic displacer mercury tube switches chosen to illustrate the invention by making the delay period depend upon the time required for a given quantity of gas to 15 flow through the space obstructed by a wad of fiber whose resistance to the flow of gas depends upon the thickness of the wad and how tight it is packed, both of which are quickly determined by skilled workmen.

20 In the drawing:

Fig. 1 is a vertical section through a fixed tube mercury switch of what is called the front contact type in which the mercury is displaced by the attraction of a cylindrical armature to 25 an electro-magnet, and the armature carries with it a displacer tube open at the bottom to mercury and at the top to the gas fill, and is constricted between the openings by a wad of cotton, asbestos, or the like; in this figure, the parts are 30 shown in the position they assume when the magnet is de-energized for longer than the time delay period.

Fig. 2 is a vertical section similar to Fig. 1 showing the effect of constricting the hollow displacer when the armature is drawn down;

Fig. 3 is a view similar to Fig. 1 showing how after the time delay interval the mercury rises within the displacer and closes the circuit;

Fig. 4 is a view similar to Fig. 1 showing how 40 some mercury is lifted with the displacer when the magnet is de-energized and the displacer rises;

Fig. 5 is a vertical section of a back contact switch in closed position;

Fig. 6 is a vertical section through the same switch immediately after the magnet is energized;

Fig. 7 is a vertical section through the same switch immediately after the magnet is de-energized;

Fig. 8 is a vertical section through the upper part of the displacer tube and three wads of cotton separated by layers of powder; and

55 Figs. 9 and 10 are vertical sections through

the upper portion of the displacer tube, and a tool used for packing the wad in the tube.

But these forms are here used because they are simple and clearly illustrate the principle of the invention, which others will readily apply 5 to a variety of switches in which the restricted flow of gas can determine the time delay.

A glass envelope 10 has lead-in wires 11 and 12 sealed through it and equipped with electrodes 13 and 14 to cooperate with purified mercury 15. 10 The lead-in wire 11 is shielded by a glass tube 16 to a suitable height and then bent over to form the electrode 14. The armature 17 is a cylinder of soft iron—in this instance, Swedish iron known as Svea. It telescopes with clearance 15 over a glass tube 18 (although ceramic or any non-magnetic material may be used) having a wide open end 19 to the mercury at the bottom and a spherical head 20 provided with a small opening 21 for gas at the top. The armature 17 20 and the displacer tube 18 are held in assembled relation by helical springs 22 which frictionally engage the projecting ends of the displacer tube.

Within the upper end, in this instance and 25 always where the gas is to flow, there is a wad 23 of cotton (or asbestos or any other fiber that will pack and will not react with the mercury) packed against the spherical head 20 and having a thickness and density determined by the desired time delay interval.

30 The envelope 10 is adjustably mounted within the pole sleeves 24 and 25 of an electro-magnet 26 by a split brass sleeve 27 that grips the envelope and has its bottom end resting on top of the sleeve 25.

In a front contact switch when the magnet is energized, the parts assume some such position as shown in Fig. 2, in which the gas fill in the area 28 of the hollow displacer tube is trapped and compressed, forcing the mercury 40 downwardly within the displacer tube to a position about like that indicated at 29. As the gas permeates the wad 23 and escapes to the upper portion of the envelope, the pressure differential on the mercury within and without the displacer gradually equalizes and the mercury rises within the displacer to about the position 30, shown in Fig. 3, closing the switch.

When the magnet is de-energized, the armature and displacer rise to some such position 50 shown in Fig. 4, and the pressure differential between the gas fill without and within the displacer causes the mercury within the displacer to rise to some such position as shown at 31 (in Fig. 4) until the flow through the wad 23 allows 55

the pressures to be equalized when the mercury assumes the position shown in Fig. 1 again, and the circuit is broken.

In a similar fashion, Figs. 5, 6 and 7 illustrate approximately the position the mercury takes in a back contact switch; in Fig. 5 when the circuit is closed; in Fig. 6 immediately after the magnet has been energized; and in Fig. 7 after the magnet has been de-energized.

10 The quantity of the fiber in the wad and the degree of pressure and the manner in which it is applied will depend partly on the nature of the fiber and partly on the time delay required. The best grades of sterilized absorbent cotton on sale 15 at drug stores have been found very satisfactory. It can be formed into wads with the fingers and pushed to position in the displacer tubes with any sort of rod. However, it is best to use a tool that will pack the edges somewhat, as illustrated at 35 20 in Fig. 10, for the nature of the material causes it to grip the walls of the tube and retain a residual compactness after the tool has been removed. In some instances, it has been found useful in making the correct time delay to insert a 25 plurality of wads in succession, pressing each down tightly as it is put in place. Where very long delay is required, powder in a layer 36 between the wads assists in constricting the flow. Alundum, carborundum, cinchonium oxide, 30 ground glass, or, generally, any ceramic or siliceous powder that will not react with mercury will be found satisfactory—the finer the powder, the greater the constriction.

The last wad of cotton should be trimmed and singed to remove frayed hairs before forcing it home.

When asbestos is used, it should be burnt or otherwise purified to prevent injury to the mercury. Other fibres should have appropriate 40 purification for the same reason.

By way of illustration of proportions, one front contact switch embodying the invention has an envelope 14½ mm. inside diameter and 128 mm. long. The armature is 1½" long, 4½" outside 45 diameter and 23/64" inside diameter. The displacer tube is 3" long, 8½ mm. outside diameter, 6½ mm. inside diameter, with a hole at the top 5/64" in diameter.

I claim as my invention:—

50 1. In a mercury tube switch relay, a sealed tube containing electrodes, a charge of mercury, a gas fill, a displacer including a long hollow body having a wide opening presented to the mercury and another opening to the gas, and means to retard 55 the flow of gas into and out of the body above the mercury including a wad of fiber in the body of sufficient thickness and density to effect the desired delay.

60 2. In a time delay relay of the class described, a sealed tube containing electrodes, a charge of mercury, a gas fill, a displacer including a tube open at the bottom to mercury and at the top to gas, and a wad of fiber packed against the top of the tube and of sufficient thickness and density 65 to effect the desired delay.

65 3. In a time delay relay of the class described, a sealed tube containing electrodes, a charge of

mercury, a gas fill, a displacer including a tube open at the bottom to mercury and at the top to gas, and a wad of fiber packed in the top of the tube to retard the flow of gas into and out of the tube, the gas opening being of sufficient size to permit substantially unrestricted flow of gas into and out of the tube.

4. In a mercury tube switch, an envelope, electrodes sealed through the envelope, a gas fill, a charge of mercury within the envelope to cooperate with the electrodes and control the circuit, means to shift the mercury to change the condition of the circuit, and means to delay the change comprising a hollow body having a passage for gas and a wad of fibrous material in the passage 15 of such thickness and density as to retard the flow of gas for a time corresponding to the delay.

5. In a mercury tube switch, an envelope, electrodes sealed through the envelope, a gas fill, a charge of mercury within the envelope to cooperate with the electrodes and control the circuit, means to displace the mercury to change the condition of the circuit, and means to delay the change comprising a hollow body open to the gas and mercury at spaced points and means to vary 25 the pressure on the mercury within the body including a wad of fiber to retard the flow of gas said fiber being of sufficient thickness and density to account for at least a substantial portion of the time delay desired.

30 6. In a mercury tube switch, an envelope, electrodes sealed through the envelope, a gas fill, a charge of mercury within the envelope to cooperate with the electrodes and control the circuit, means to displace the mercury to change the condition of the circuit, and means to delay the change comprising a hollow body having an opening below for mercury and above for gas and means to restrict the flow of gas and thereby control the period of operation comprising a wad of 40 fiber in the hollow body of sufficient thickness and density to account for at least a substantial portion of the time delay desired.

35 7. In a mercury tube switch, an envelope, electrodes sealed through the envelope, a gas fill, a charge of mercury within the envelope to cooperate with the electrodes and control the circuit, a displacer in the envelope including a glass tube open below to the mercury and above to the gas, and means to restrict the flow of gas including a 50 wad of fiber in the upper portion of the tube and packed sufficiently to account for at least a substantial portion of the time delay desired.

45 8. In a mercury tube switch, an envelope, electrodes sealed through the envelope, a gas fill, a charge of mercury within the envelope to cooperate with the electrodes and control the circuit, means to displace the mercury to change the condition of the circuit, and means to delay the change comprising a hollow body having a passage for gas and a quantity of powder in the passage, the powder particles being of such quantity and size and so packed together as to account for 60 at least a substantial portion of the time delay desired.

65 CARL H. LARSON.
